UNITED STATES PATENT OFFICE.

HERMAN R. UECKERMAN, OF EMSWORTH, PENNSYLVANIA.

COMBINATION HOUSEHOLD-TOOL.

SPECIFICATION forming part of Letters Patent No. 618,258, dated January 24, 1899.

Application filed August 30, 1898. Serial No. 689,881. (No model.)

To all whom it may concern:

Be it known that I, HERMAN R. UECKERMAN, a citizen of the United States, residing at Emsworth, in the county of Allegheny and 5 State of Pennsylvania, have invented new and useful Improvements in a Combination Household-Tool, of which the following is a specification.

This invention relates to combination household-tools; and the object thereof is to provide a tool which combines in one implement several of the more useful articles of everyday use.

The invention consists in the novel features 15 of construction and in the combination and assemblage of parts hereinafter fully described and claimed, and illustrated by the accompanying drawings, in which—

Figure 1 is an elevation of the implement 20 with its arms opened or separated. Fig. 2 is an elevation showing the opposite side from that illustrated in Fig. 1, with the arms closed together. Fig. 3 is a cross-sectional view on line 3 3 of Fig. 2. Fig. 4 is a detail view of 25 the end can-opener portion of the implement.

The tool consists, essentially, of the two arms A and B, hinged together at one end by rivet or screw C. Hinge-head D constitutes the pinching-heel or fulcrum for can-opener blade 30 E, the latter being formed with guard F, which overhangs the can edge when in use and holds the blade from running inward from the edge while advancing during the cutting operation. Arm B adjacent the hinge is formed

35 with lemon-squeezing bowl G, while immediately over said bowl arm A is formed with the complementary plunger or presser H. Next in order on arm A is the laterally-projecting serrated hammer-head I for tendering 40 meat, crushing ice, &c., while in line with said hammer on arm B is ice-chopper J. It will be noted that arms A and B engage flatly in line with hammer I and chopper J, so that the force of a blow struck by either of said 45 tools is borne by both arms, each arm reinforcing the other. The arms are held together against lateral deflection by lugs K, projecting from arm B and embracing arm A.

Wrench-cavity K' may be formed in the end 50 gaging surfaces of the arms, as shown, and the same also may be used for holding nuts while cracking. The central portions of the arms are oppositely curved at L to form, when

closed, a circular jar-top wrench. These curved wrench members carry the pointed 55 oppositely-sharpened hook-shaped knives M, which, with the tool laid flatly on the top of a tin can, are adapted to be forced into the opposite vertical sides thereof, just beneath the top, and by rotating the tool the can-top 60 is cut off. The arms are continued to form convenient handles N, one of said handles terminating in screw-driver O and the other handle forming at its extremity the tack-claw P. Thus a plurality of the most necessary 65 household-tools are conveniently assembled in a single implement, and the same being stoutly made each element has full capacity for the work required of it without strain or injury to the other elements. 70

The distance between the impact parts and the handles is such as to afford the former proper length of stroke. Were said parts located at or adjacent to the pivot of the arms they would be too far from the handles and 75 their use would be cumbersome and inconvenient. A further advantage incident to the arrangement of elements here shown is that the lemon-squeezing parts do not receive the direct force of blows of the impact elements, and having position beyond said elements rather than between them and the handles they are subjected to a minimum amount of jar when striking with the implement. 80

Having thus fully described my invention, what I claim as new, and desire to secure by Letters Patent, is—

The combination of two separable arms curved oppositely to form a combined jar-top 90 wrench and tin-can embracer, and inwardly-pointing knives secured to the curved arms for the purpose described, said knives being in a plane parallel with the plane of the arms, the knife edges stopping short of the concave 95 edges of the arms, whereby the device may wrench a jar-top without interference from the knives, substantially as set forth.

In testimony whereof I have hereunto set my hand in presence of two subscribing witnesses.

HERMAN R. UECKERMAN.
